UNITED STATES PATENT OFFICE.

JOHN AINSWORTH RICE, OF BLAND, TERRITORY OF NEW MEXICO, ASSIGNOR OF ONE-HALF TO CHARLES W. GRAVES, OF BLAND, TERRITORY OF NEW MEXICO.

TELEPHONE ATTACHMENT.

SPECIFICATION forming part of Letters Patent No. 688,124, dated December 3, 1901.

Application filed March 29, 1901. Serial No. 53,546. (No model.)

To all whom it may concern:

Be it known that I, JOHN AINSWORTH RICE, a citizen of the United States, and a resident of Bland, in the county of Bernalillo and Territory of New Mexico, have invented a new and Improved Telephone Attachment, of which the following is a full, clear, and exact description.

This invention relates to attachments for telephones; and the object is to provide in connection with a telephone an automatic relay for operating vibrating electric bells remote from the telephone, such as in different parts of a machine-shop, where a loud or distinct alarm is necessary to call attention to the telephone.

I will describe a telephone attachment embodying my invention and then point out the novel features in the appended claims.

Reference is to be had to the accompanying drawings, forming a part of this specification, in which similar characters of reference indicate corresponding parts in all the figures.

Figure 1 is an inside view of the door of a telephone-box, showing an attachment embodying my invention as applied thereto. Fig. 2 is a similar view, but showing the parts in inactive or normal position. Fig. 3 is a section on the line *x x* of Fig. 2, and Fig. 4 is a diagrammatic view illustrating the electric circuit.

Referring to the drawings, 1 designates a telephone-box door, on the outer side of which the gongs 2 are mounted and which are sounded by a clapper 3, operated from the magneto in the usual manner. The relay comprises two arms or levers 4 5, mounted to swing on the inner or outer side of the door 1. As here shown, these arms or levers are crossed and swing on a pivot 6, which is in electrical connection with the line-wire 7 of a local circuit. The upper ends of these arms or levers embrace the opposite sides of the clapper 3, and the lower ends are turned outward to engage, respectively, with spring-yielding contacts 8 and 9, attached to the ends of a bracket 10, secured to the inner side of the door, and this bracket 10 is in electrical connection with the wire 11 of the local circuit. I have shown a battery 12 arranged in this local circuit and also a vibrating bell 13. It is to be under-

stood, however, that while I have shown but one vibrating bell a greater number may be included in the circuit.

In operation when the magneto of the telephone is operated and the electromagnet 14 is energized the clapper 3 will be vibrated to sound the gongs 2 alternately in the usual manner. This vibrating movement of the clapper will cause a vibrating movement of the arms or levers of the relay, causing them to alternately make and break contact through the contacts 8 and 9, thus closing the local circuit and sounding an alarm or alarms therein.

The lower ends of the levers or arms 4 and 5 being heavier than the upper ends, they will be caused to automatically swing to normal position, or, in other words, when one arm is operated upon by the clapper the other will follow the clapper to the extent of its movement.

Having thus described my invention, I claim as new and desire to secure by Letters Patent—

1. In connection with a telephone, a local circuit containing an alarm or alarms, and a circuit-closer in or outside of the telephone-box for controlling said circuit, the said circuit-closer being operated by both the back and forth movements of the clapper of the telephone-bell and having normal connection with the local circuit, substantially as specified.

2. In connection with a telephone, a local electric circuit in which an alarm is arranged, a circuit-closer within or outside of the telephone-box and having connection with said local circuit, the said circuit-closer comprising swinging arms having connection with the vibrating clapper of the telephone-bell, and contact-fingers coacting with said arms, the said contact-fingers also being in the electric circuit, substantially as specified.

3. In connection with a telephone, a local circuit in which an alarm is arranged, a circuit-closer in or out side of the telephone-box and consisting of two arms crossed and mounted to swing independently one of the other, the upper portions of said arms engaging with the clapper of the telephone-bell, spring contact-fingers adapted to be engaged by the

lower portions of said arms, and connections between said arms and fingers and the local circuit, substantially as specified.

4. In connection with a telephone, a local electric circuit, an alarm or alarms arranged in said circuit, a circuit-closer consisting of two arms mounted to swing independently upon the inner or outer side of the telephone-box door, the said arms being crossed and 10 having their upper ends engaging with the telephone-bell clapper, the lower ends of said arms being turned outward, and contact-fingers

adapted to be engaged by said outwardly-turned ends, the arms and contact-fingers being connected in the local circuit, substantially as specified. 15

In testimony whereof I have signed my name to this specification in the presence of two subscribing witnesses.

JOHN AINSWORTH RICE.
